UNITED STATES PATENT OFFICE

2,635,652

SABER TYPE JIGSAW BLADE

Alvin Norquist, Seattle, Wash.

Application October 20, 1947, Serial No. 789,945

2 Claims. (Cl. 143—133)

1

This invention relates to jig-saws, and for its general object aims to provide a perfected jig-saw of inexpensive and simple construction and one which, while applicable to general work, peculiarly adapts itself to a quick and accurate cutting of balsa and other wood or cardboard materials employed by model makers in the production of small-scale airplanes, vessels and the like.

The invention has the further and important object of providing a new type of cutting blade and one, more especially, which is sectionally of a substantially square shape presenting cutting teeth upon each of the four sides thereof and thus enabling the blade to traverse sharp-angle turns.

It is further object still to provide a jig-saw including the usual work-supporting table and characterized in that the blade has sufficient rigidity to enable the same to be supported from below this table only, with the working plane being consequently left entirely free of any obstruction to permit the work to be freely manipulated regardless of the length of the board being sawed.

With the foregoing and other objects and advantages in view and which will appear and be understood in the course of the following description and claims, the invention consists in the novel construction and in the adaptation and combination of parts hereinafter described and claimed.

In the drawing:

Figure 1 is a side elevational view illustrating a jig-saw constructed in accordance with the preferred embodiment of the present invention.

Fig. 2 is a front elevational view thereof.

Fig. 3 is a top plan view with parts broken away and shown in section; and

Fig. 4 is a fragmentary longitudinal vertical sectional view taken to an enlarged scale on line 4—4 of Fig. 3.

According to the present invention there is provided a machine standard designated by the numeral 10 and which is or may be a unit casting presenting an overhang at the top and having a flanged base for the reception of securing bolts 11. The over-hang is drilled to provide a vertical bore, and there is also provided a horizontal bore located adjacent the base of the standard, with each of said bores being press-fitted with bushings, as 12, and having the usual lubricating felts 13 fed by an oil cup 19. Journaled in said bushings, and arranged for reciprocal sliding movement and for rotary movement, respectively, there is provided a spindle 14 and a drive shaft

2

15 with the shaft receiving its drive by means of a belt 16 passing about a pulley 17 and driven from a suitable source of rotary power such as an electric motor (not shown). The shaft projects by its frontal end forwardly beyond the standard and upon this protruding end and secured by a set screw or the like thereto is a flywheel 18. Crank action is transmitted from this flywheel to a connecting rod 20 finding offset 10 pivotal attachment to the face of the wheel, and the other end of the rod connects as at 21 with the lower end of the reciprocally movable spindle.

Designated 22 is a work-supporting table surmounting the standard, and this table, while it 15 might feasibly be produced as an integral part of the standard, is desirably made removable and is composed of a steel plate having a severality of depending hollow legs 23 welded to its underside through which securing bolts 24 are passed to 20 secure the table in position. The table has a central aperture 25 arranged to lie in perpendicular alignment with the slide axis of the spindle, and the legs, shown as being three in number, occupy positions equidistantly spaced at intervals 25 of a circumference taken concentric to this axis.

The spindle is made hollow at its upper end to describe a socket having a square shape in cross-section, and this hollowed extremity, by reciprocal movement of the spindle, works within the space lying between the top of the standard and the bottom of the table. Denoted 26, the saw-blade of the machine likewise has a square shape in cross-section and fits snugly by its lower end within said socket, being firmly secured to the spindle by a set-screw 27 accessible through 30 the openings between the legs. In forming the teeth of the saw-blade, the latter is cut to give to each of the four sides of the blade a sharp-edged fluting, and these flutes, which extend transverse to the blade's length, are by preference 35 made to register the flutes of one side with the flutes of adjacent sides. The teeth themselves are desirably of the buttress type, and which is to say teeth of which one face is disposed perpendicular, or nearly perpendicular, to the axis of

40 the blade while the other face is inclined to such axis. In mounting the saw-blade, the same is applied such that the abrupt faces lie upon the underside of the teeth, thus performing the cutting function by the down-stroke of reciprocation.

50 Distinguished from jig-saws as they have been heretofore designed, and namely such as provide top and bottom guides for the saw-blade and hence require that the blade be of a predetermined length with connector devices at each of 55 the two ends, the saw-blade of the present in-

vention is attached only at one end and the length is unimportant other than for a self-evident necessity that the upper extremity extend above the level of the table-supported work. In consequence thereof, it becomes possible to supply to the user a blade somewhat longer than would normally be required and as continued use of the blade eventually dulls the comparatively few teeth which, in any jig-saw, perform the actual work of sawing, the operator need only cut off a short section from the bottom end of the blade and thus enable the blade to be lowered to the extent necessary to bring a fresh series of teeth into the cutting zone. In lieu of cutting off a section of the blade, the spindle could, perchance, be hollow throughout its length and consequently allow the blade to be pushed downwardly into the socket as successive series of teeth become worn.

The manner by which my square-sectioned saw-blade allows the operator to work along a given saw-cut and, reaching a sharp-angled turn, change direction and then work in a direction angular to the former line of travel will, it is thought, be clearly understood, the teeth upon one side of the blade performing the cutting function as the blade traverses one said saw-cut and the teeth upon an adjacent side of the blade thereupon picking up the work as the directive travel changes. Where the turn in question is a right-angled turn, it becomes unnecessary to turn the work in any degree whatsoever, the operator simply imparting to the work in a directive movement at right angles to the previous line of movement. For negotiating turns other than a right-angled turn, the degree to which the work must be turned is at most 45° due to the fact that two cutting faces removed 90° from one another are always available. It should be here pointed out that a three-sided blade could be employed in lieu of the square blade which I have illustrated, and while a blade of this form would be less desirable the same would suffice to give to the blade the necessary rigidity which enables the present machine to eliminate the objectionable top guide which is common to previous jig-saws, and with its teeth on all three sides would allow sharp-angled turns to be accurately negotiated, necessitating,

however, somewhat greater maneuvering of the work.

The invention, the manner of its employment, and its accomplishments are believed to be clearly understood from the foregoing. While having illustrated and described my now-preferred embodiment, modifications may obviously be resorted without departing from the spirit of the invention and it is my intention that the here-to annexed claims be read with a scope fully commensurate with the broadest interpretation which the employed language fairly permits.

What I claim is:

1. A jig-saw blade produced from sectionally square stock of uniform gauge throughout its length and formed upon each of the sides with a series of uniformly spaced buttress-type transverse teeth so located, as between the teeth of the several sides, that each of the teeth of a respective said side exactly register with the teeth of the two adjacent sides, the surfaces of the blade which are defined between the successive teeth defining substantial facets of an isosceles trapezoid shape.
2. The jig-saw blade of claim 1 in which the non-parallel sides of said isosceles trapezoid facets are substantially longer than the shorter of the two parallel sides.
